UNITED STATES PATENT OFFICE

HALFDAN CARLSEN, OF NEW YORK, N. Y.

SAFETY GAS BURNER

Application filed March 24, 1930. Serial No. 438,541.

This invention relates to gas stoves and in particular to an auxiliary jet arranged to be disposed adjacent the main burner so that should the main burner become extinguished accidentally, the auxiliary jet will relight the same.

The cause of many deaths by accidental asphyxiation is the boiling over of a vessel so that the contents of the vessel extinguishes the gas flame and subsequently permits the gas to escape with detrimental results. In order to overcome this danger, I have provided adjacent the burner, another safety burner in which use is made of the full pressure of the gas line to project a jet of flame from the safety burner across the main burner so that should the flames of the main burner be extinguished accidentally, the gas will be reignited and its escape prevented.

In order that the safety light may be manufactured at small cost, and in order that it may operate efficiently and be substantially fool-proof and at the same time prevent the waste of gas, I have provided a hood which is arranged to be cast integral with the safety light and also a valve so that the amount of gas flowing through the safety light may be controlled.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 is a plan view of a gas burner and feed pipe in the latter of which is incorporated my improved safety burner.

Figure 2 is a view in side elevation of the burner and safety burner as illustrated in Figure 1.

Figure 3 is an enlarged view in sectional elevation showing the construction of my improved safety burner, and

Figure 4 is a section taken through the feed

pipe showing the connection therewith of the safety burner.

Referring to the drawings in detail, 5 indicates a gas burner of any approved type to which illuminating gas is fed through the medium of the feed pipe 6. The burner 5 is arranged to be positioned beneath a pot supporting grating or grille so that the flame from the burner may impinge upon the bottom of the vessel. In order that the escaping gas from the burner may be at all times kept ignited, I have provided a safety light or jet consisting of an auxiliary pipe 7 which is closed at its upper end as at 8 and at its lower end is provided with the cut-out portion 9 and in the wall thereof, a gas passage 10, the object of the opening 10 being to facilitate the passage of the gas through the feed pipe 6 so that the operation of the burner will not be materially interfered with. The upper end of the auxiliary pipe 7 is cast to provide a thickened portion 11 in connection with which is integrally formed, a substantially semi-circular shaped hood 12. This hood is arranged to cover the end of a jet tube 13 which is forcibly fitted into the enlarged portion 11 of the auxiliary pipe 7 so that the flame emerging therefrom, as indicated by the numeral 14—A in Figure 2, is protected at the point where it emerges from the jet tube and will not be extinguished by a gust of wind or the boiling over of the contents of a vessel disposed above the main burner 5.

It will be noted that the hood 12 being of a substantially semi-circular shape, is greatest in width at the lower edge thereof so that in burner constructions in which the pipe 6 is substantially flush with the burner and where little space is provided between the burner and the pot holding grating or grille, the safety light can be placed very close to the pipe 6 by providing a short auxiliary pipe 7, it being evident that the outer edges of the hood 12 will fit down over the pipe 6 so that the auxiliary burner can fit between the pipe and the grille.

In order that the amount of gas passing through the jet tube 13 may be regulated, I have provided a threaded needle valve 14

which is adjustably positioned in the auxiliary pipe 7 in diametrical alignment with the jet tube 13 so that the pointed end 15 thereof may engage the end of the jet tube 13 to regulate the flow of gas therethrough and consequently, the length of the flame 14—A exuding from the jet tube 13.

A suitable finger disk 16 is employed on the end of the needle valve 14 for the purpose of revolving the same so that its adjustable movement is afforded through the medium of its threaded connection with the auxiliary pipe 7. The threads 17 formed on the lower end of the auxiliary pipe 7 permit an adjustable threading in of the pipe 7 into the feed pipe 6 so that the height of the hood 12 may be regulated relatively to the upper surface of the burner 5 and consequently the flame 14—A may be arranged to shoot across the upper surface of the burner so that the moment the flames of the burner are accidentally extinguished, the gas emitting from the burner openings will be immediately ignited.

25 The integral casting of the hood 12 in connection with the auxiliary pipe 7 to make a unitary structure, not only saves the expense of manufacturing but eliminates any necessity of adjusting the hood relatively to the auxiliary pipe. The slight space 18 left between the rear edge of the hood and the auxiliary pipe 7 provides for the admission of air for the promotion of combustion.

It will be evident that the jet tube 13 being of relatively smaller diameter than the auxiliary pipe 7, will provide for the emission of a thin jet of gas that will provide the long tongue of flame 14—A due to the pressure in the feed pipe 6 and auxiliary pipe 7.

40 The apron portion 19 of the lower end of the auxiliary pipe 7, as provided by the cut out 9, acts to divert the gas so that it passes up the auxiliary pipe so that a constant stream of gas through the jet tube is provided.

It is evident, therefore, that I have provided an improved auxiliary burner in the nature of a safety light which will maintain the gas emitting from a burner ignited, after the same has been accidentally extinguished, to prevent the escape of the gas and protect human life.

It is evident, also, that by providing a restricted jet tube in connection with a burner of the type described, that attention to the lighting of the safety light is unnecessary because the pressure of the gas emitting from the jet tube 13 is such that the safety light is ignited at the same time that the burner is lit but thereafter, the boiling over of a pot or other vessel will not be sufficient to ignite the safety light and the burner flame will be maintained even after repeated extinguishing by liquid or wind pressure.

45 While I have illustrated and described my

invention with some degree of particularity, I realize that in practice various alterations therein may be made without departing from the spirit of the invention or the scope of the appended claims.

What I claim is:—

1. The combination with a burner and gas feed pipe therefor, of a safety light comprising an auxiliary pipe attached to said feed pipe, a hood on said auxiliary pipe, a gas jet in the auxiliary pipe extending beneath said hood, and the vertical edges of the hood adjacent the auxiliary pipe being spaced from said auxiliary pipe to provide an air passage.

2. The combination with a burner and gas feed pipe therefor, of a safety light comprising an auxiliary pipe threaded into said feed pipe, a jet in the auxiliary pipe, an adjusting screw for regulating the flow of gas through said jet, a semi-circular hood formed integral with said auxiliary pipe and depending to protect the jet, and the vertical edges of the hood adjacent the auxiliary pipe being spaced therefrom to provide an air passage.

3. The combination with a burner and a gas feed pipe therefor, of a safety light comprising an auxiliary pipe threaded into said feed pipe, a jet in the auxiliary pipe, an adjusting screw for regulating the flow of gas through said jet, a substantially semi-circular hood formed integral with said auxiliary pipe and protecting said jet, and having its vertical edges adjacent the auxiliary pipe spaced therefrom to provide an air passage, and said auxiliary pipe having an opening at one side thereof in that portion disposed within said feed pipe.

In testimony whereof, I have signed my name to this specification this 13th day of March, 1930.
